TYPEWRITING MACHINE

Application filed June 11, 1927. Serial No. 198,265.

This invention relates to improvements in typewriting machines, particularly the traveling platen carriage and parts associated therewith.

5 Features and objects of the invention include the provision of a sheet metal traveling carriage for the platen having opposed relatively adjustable raceway portions, which carriage is light but rigid and is so constructed that it may be manufactured at low cost; the provision of an adjustable sheet metal carriage formed from two metal blanks and having an integral raceway element on each section, one of the sections having 10 integral platen-supporting end plates and an integral carriage feed rack; the provision of improved antifriction supporting means for a platen carriage; the provision of improved means for effecting adjustments between 15 opposed raceways of a platen carriage; the provision of means whereby correct adjustment between the feed rack and feed pinion for the platen carriage is facilitated; the provision of means for taking end thrust resulting from line spacing and carriage returning 20 operations of a line space device mounted on the carriage; the provision of an improved construction and arrangement of the carriage advancing means; and the provision of an 25 improved means for limiting the maximum travel of the carriage.

Other features and objects of the invention will appear from the following description in detail of the preferred embodiment of the 30 invention illustrated in the accompanying drawings wherein is illustrated a platen carriage and bed and associated parts especially adapted for use in the Corona Four typewriting machine.

40 In the drawings:

Figure 1 is a plan view of the carriage and bed, the carriage adjusting implement being shown in position for use at one of the adjusting points;

45 Fig. 2 a sectional view on the line 2—2 of Fig. 3;

Fig. 3 an end view of the carriage and bed, these parts being shown in the rearwardly 50 and downwardly tilted position in which they

are supported by the case shift mechanism of the Corona Four machine;

Fig. 4 a fragmentary bottom plan view of the carriage bed, the heads of the bracket fastening screws being broken away;

55 Fig. 5 a sectional view on the line 5—5 of Fig. 1, but showing the carriage and bed tilted as in Fig. 3;

Fig. 6 a perspective view looking from the rear and showing the two sections of the carriage detached;

60 Fig. 7 a perspective view of the carriage adjusting implement;

Fig. 8 a fragmentary sectional view of the carriage taken on the line 8—8 of Fig. 5;

65 Fig. 9 an enlarged sectional view on the line 9—9 of Fig. 2, the carriage and bed being tilted as in Figs. 3 and 5;

70 Fig. 10 a fragmentary sectional view taken through the centers of the rack-forming holes drilled in the raceway flange forming portions of the two carriage blanks and the carriage bed blank prior to bending of the raceway flange forming portions into V-form;

75 Fig. 11 a section on the line 11—11 of Fig. 13;

Fig. 12 a fragmentary view showing the roller-engaging or inner side of one of the carriage raceway flanges;

80 Fig. 13 a section on the line 13—13 of Fig. 12; and

Fig. 14 a perspective view of the carrier for the antifriction bearing rollers.

The traveling platen carriage consists in its entirety of a front section formed of a single piece of sheet steel, a rear section formed of a single piece of sheet steel, six screws for holding the two sections together in adjusted relation, and a seventh screw for tying together two bracing lugs formed respectively on the main body of the front section and on one of the end plate portions of said section, as hereinafter described. The carriage bed is formed of a single piece of sheet steel.

85 90 95 100 The main front section of the carriage has a flat rectangular bottom plate 1, a pair of upstanding platen supporting end plates 2 bent up from the ends of the bottom plate, a raceway flange 3 bent down from the front edge

of the bottom plate and extending substantially the full length of the carriage, and a flange 4 bent down from the rear edge of the bottom plate, said flange 4 extending substantially the length of the carriage in a plane 5 perpendicular to the bottom plate and carrying along its lower edge a forwardly extending portion lying in a plane parallel with the base plate and provided with teeth along its forward edge to form an integral carriage feed rack 5 which extends from end to end of flange 4.

The rear section of the carriage comprises a flat plate 6 overlapping for the greater 15 part of its width from front to rear the bottom plate 1 of the front section. The plate 6 extends substantially the full length of plate 1 and overlaps plate 1 a substantial distance from front to rear, preferably about 20 half the distance between the front and rear edges of plate 1, and is formed at its rear edge intermediate its ends with a downwardly bent raceway flange 7 opposite the raceway flange 3 on the plate 1. Flange 7 extends substantially the full length of the carriage a short distance behind flange 4 25 on plate 1 and the plate 6 is formed at its rear edge adjacent opposite ends of said flange 7 with two rearward extending lugs 30 8 and 9 lying in the plane of the plate, the lug 9 having an upstanding rear portion 9^a, and said lugs serving as carriage traveling limiting stops, as more fully hereinafter described.

35 The overlapping plates 1 and 6 are clamped tightly together in adjusted relation by means of six screws 10 the shanks of which pass downward through fore and aft extending slots 11 in plate 6 and are threaded into screw holes 12 in plate 1. The screw holes and 40 slots are arranged so that the six fastening screws are staggered with relation to a line extending longitudinally of the carriage, one row of screws 10 clamping the plate 6 to plate 1 near the rear edge of plate 1 and the other row of screws 10 clamping the plates together near the forward edge of plate 6. It will be obvious that plate 1 is 45 greatly stiffened by raceway flange 3 and by flange 4 and integral rack 5, that plate 6 is stiffened by raceway flange 7, and that the broad overlap and staggered fastening arrangement for the two plates affords a firm non-tilting connection between the two 50 carriage sections and greatly strengthens the main body of the two-part carriage.

The platen 13 is mounted on the platen shaft 14 which is journaled adjacent its ends in the cylindrical inner end portions 15^a of 55 two cupped bearing bosses formed at the inner faces of the carriage end plates 2 by a metal-drawing operation. A somewhat broader and smoother bearing for the platen shaft is thus afforded on each of the carriage end plates than would be the case if the

shaft were journaled in holes punched through the plates. These drawn bosses 15 also serve to somewhat stiffen the carriage end plates. The platen shaft is passed through the bearing bosses and the platen 70 in the manner usual in the Corona Four machine, and has mounted on its ends two sleeves 16 which carry the usual finger wheels or platen knobs, not shown. In the particular construction shown the left-hand bearing boss 15 is of somewhat larger diameter than the right-hand bearing boss, since the left-hand finger wheel sleeve 16 in the construction shown passes through the boss and into the platen to control a suitable fractional line-spacing device.

75 A suitable line spacing mechanism (including a line spacing and carriage returning lever 17 which is provided with a pawl, not shown, for rotating the ratchet wheel 19 connected with the platen 13) is mounted on a bearing post 20 carried by a sheet metal bracket 18. Bracket 18 is attached by three screws 21 to the outer face of the left-hand end plate 2 of the carriage, the screws 21 being threaded into screw holes 22 in the end plate. The line spacing mechanism shown is the line-space mechanism employed in the Corona Four machine and is of a well-known construction. The left-hand carriage end plate which supports the line spacing device is braced against strains incident to carriage returning and line spacing operations of the line spacing lever 17 by means of a pair of bracing lugs 23 and 24. The lug 23 is bent upwardly from the forward edge of the carriage plate 1 between the left-hand end plate 2 and the left-hand end of the raceway 3, and lies flatwise in a plane perpendicular to the plane of said plate 1. The lug 24 is bent inwardly from the front edge of the left-hand end plate 2 and lies flatwise against the front face of the lug 23. The overlapping lugs are rigidly locked together by means of a fastening screw 25 the shank of which passes through registering holes in the overlapped lugs. Preferably the hole in the lug 24 is not threaded and that portion of the screw shank which passes through said lug 24 is not threaded, the hole in lug 23 being threaded and the screw shank being threaded only through the threaded hole in the lug 23, as indicated in Fig. 9.

100 The end plates of the carriage are provided at their rear ends with bearing apertures 26 for the margin stop bar of the Corona Four machine. The right-hand end plate is provided with an aperture 27 and the base plate 1 is provided with screw holes 28, all for connection of the several parts of the paper feed mechanism of the Corona Four machine with the front section of the carriage, while the left-hand end plate has an integral lug 29 punched inward therefrom and forming an anchor for the return spring of the margin 105 110 115 120 125 130

stop bar of said machine. The upstanding portion 9^a of the lug 9 on the carriage section 6 forms an anchor for the return spring of the cast-off means of the paper feed mechanism of the Corona Four machine. The paper feed mechanism and the margin stop bar of the Corona Four machine are constructed substantially as shown in the patent to Armstrong, No. 1,619,013, dated March 1, 1927.

5 The right-hand end plate 2 is provided with a screw hole 30 registering with the rearmost screw hole 22 in the left-hand end plate 2, screws in these two screw holes being employed as pivots for the escapement release bail of the Corona Four machine. The two end plates have lugs 31 and 32 punched outwardly therefrom to form stops for the paper-release bail. The right-hand end plate of the carriage is formed with an integral lug 33

10 for supporting the guide screw of the carriage-centering stop of the Corona Four machine, and is also formed with an integral lug 34 forming an anchor for the return spring of the carriage-centering stop which is pivoted on the same screw in hole 30 as the right-hand side arm of the escapement release bail.

15 The carriage bed is stamped up from a single piece of sheet metal and comprises a flat rectangular base plate 35 having a front raceway flange 36 bent upward from the forward edge of said plate and a rear raceway flange 37 bent upward from the rear edge of said plate. The plate 35 and the flanges 36 and 37 are approximately the same length as the raceway flanges of the carriage and extend upward between the carriage raceway flanges, the raceway flange 37 on the carriage bed extending upward between the feed rack 20 supporting flange 4 and the raceway flange 7 on the carriage.

25 The portions of the raceway flanges 36 and 37 which extend between the raceway flanges 3 and 7 are pressed inwardly toward each other to form a V-shaped outwardly facing channel in each of the carriage bed flanges. The portions of the carriage flanges 3 and 7 which overlap the carriage bed flanges are pressed outwardly to form an inwardly facing V-shaped channel in each flange. A sheet metal anti-friction roller carrier 38, of well known construction, is housed in the front raceway formed by the flanges 3 and 36, and a similar anti-friction roller carrier 38 is housed in the rear raceway formed by the flanges 7 and 37. A pair of antifriction rollers 39 are rotatably mounted at each end of each carrier 38 with the axes of the two rollers forming each pair disposed at right angles to each other, so that the two rollers of each pair travel on different sets of opposed parallel faces of the complementary raceway flanges between which the carrier 38 travels, in the well known manner.

30 In order that the antifriction rollers may always travel one-half the distance traversed by the carriage, a geared driving connection is provided between each carrier and the carriage and bed. This geared connection comprises a sheet metal pinion 40 journaled on a pivot pin 41 secured to the carrier 38, the teeth of said pinion entering holes H extending through the raceway flanges at the apex of the V-shaped roller-receiving channel in each flange, the webs of metal T between the holes in each flange forming rack teeth with which the pinion teeth mesh.

35 The rack tooth portions T of the raceway flanges are formed in a special manner which will be now described, attention being called to Figs. 10 to 13 of the drawings. The raceway-forming portions R of the blanks from which the carriage sections and the carriage bed are formed each have drilled therein, before the several blanks are bent up into shape, a row of holes which are cylindrical, as shown at H' in Fig. 10, for approximately one-half the thickness of the blank, and are frustoconical, as shown at H² in Fig. 10, for the remaining portion of the thickness of the blank, the ends of the holes of greatest diameter being located at that face of the portion R of the blank which is to form the tracks for the antifriction rollers. When the previously drilled raceway flange-forming portion R of each blank is bent into channel form, as shown in Figs. 11 to 13, the flaring part H² of each hole assumes an elliptical form, the upper and lowermost portions of the wall of the flaring hole portion approaching each other due to the folding of the raceway flange portion of the blank along a line through the axes of the drilled holes, and the side portions of the wall of the flaring hole portion H² are pressed more nearly into parallelism, due to compression of the webs of metal between the holes along the concave face of the folded raceway portion of the blank, all as shown in Figs. 11, 12 and 13. In other words, during the folding operation the metal of the wider portions of the webs between the holes adjacent the convex face of the bent or folded blank is stretched while the metal of the remaining portion of the thickness of the webs is compressed and expanded laterally at the concave face of the bent or folded blank where the webs are narrowest, and the one-half of each web above the line of fold will approach the one-half of the web below the line of fold at the concave face of the folded blank. The result of forming the teeth T in this manner is that the webs of metal forming the teeth T will have substantially less bevel after the raceway flange is bent to final form, since the metal forming the wider outer portions of the webs will be somewhat stretched vertically and contracted laterally while the metal forming the narrower beveled inner portions of the webs will be compressed and somewhat widened laterally.

It will be observed that by this arrangement teeth T are formed which are slightly beveled at each side where they are engaged by the edges of the teeth of the roller carrier driving pinion 40 in such manner as to facilitate the meshing with the pinion and rack teeth, and also that the holes H may be drilled while the blank is in its original flat form. The formation of the teeth after the raceways were bent into form would be a relatively difficult and expensive operation. If holes cylindrical throughout were drilled while the blanks were in their flat state, the inner ends of the holes would be contracted and the tooth-forming webs would be of undesirable form for meshing of the pinion teeth therewith. Moreover, if previously drilled cylindrical holes were employed it would be necessary to drill the holes of greater diameter than is the case with flaring holes of the kind illustrated, in order that the inner ends of the holes in the blank after the bending of the blank into final form may be large enough to accommodate the pinion teeth. This would result in weakening the raceway flange and also result in the formation of teeth T which would be narrower than in the case shown and correspondingly weaker. This is undesirable since the carriage and bed blanks are formed of thin sheet steel and the holes H and teeth T and the pinion teeth are necessarily small, the parts being illustrated in full size in Figs. 1 and 2.

The rack teeth T extend approximately one-quarter the length of the raceway flanges at both sides of mid-length of the carriage bed, and the carriage stop lugs 8 and 9, heretofore described, are adapted to cooperate with companion stops on the carriage bed to limit the maximum travel of the carriage and prevent jamming of the pinion 40 in the raceway beyond the ends of the rack teeth T. The stop means on the carriage bed comprises a bracket 42 held at its lower end to the bottom face of the carriage bed 35 by a pair of fastening screws 43 and extending upwardly behind the rear raceway flange 7 of the carriage. The screws 43 extend through slots 44 in the bracket and are threaded into the bottom plate 35 of the carriage bed, the slots extending longitudinally of the carriage bed to afford adjustment of the bracket 42 transversely of the machine. At one side thereof the bracket 42 is formed with a stop lug 45 extending upwardly and forwardly over the carriage raceway flange 7 into the path of travel of the carriage stop lug 8, and at its opposite side said bracket is formed with a similar stop lug 46 extending into the path of the carriage stop lug 9.

Means are provided whereby the two sections of the carriage may be adjusted relatively to each other in fore-and-aft direction with ease and great precision so that the anti-friction rollers will travel easily but without

permitting any side play between the carriage and bed throughout the limit of travel of the carriage over the bed. The base plate 1 of the forward section of the carriage is provided with a series of round holes 47 adjacent its rear edge spaced apart longitudinally of the carriage, as shown in Figs. 1 and 6. The plate portion 6 of the rear section of the carriage is provided with a series of rectangular holes 48 spaced apart longitudinally of the carriage and registering with the holes 47 in the front section. The holes 48 are larger than the holes 47, the latter holes being disposed approximately centrally of the holes 48.

The length of the adjusting slots 11 is such that the two sections of the carriage, while loosely connected by the clamping screws 10, may be first lowered over the carriage bed about the antifriction bearing devices and the carriage then contracted to confine the anti-friction devices in the raceways and effect meshing of the driving pinions 40 of the roller carriers 38 with the teeth T of the associated racks formed in the raceway flanges. The clamping screws 10 are then partly tightened sufficiently to prevent accidental expansion of the carriage, but not sufficiently to prevent forcing the two carriage sections apart or toward each other by means of the adjusting implement shown in Figs. 1 and 7.

The final accurate adjustment of the carriage is then made by means of this adjusting implement. This implement comprises a shank portion 49, carrying a handle cross-bar 50 at one end, and having a reduced cylindrical portion 51 at its opposite end forming a sub axle adapted to rotatably fit in either of the holes 47 in the front section of the carriage. A cam plate 52 is tightly swaged on the reduced shank portion 51 at the upper end of the reduced shank portion so as to turn with the shank. It will be obvious that with the clamping screws 10 partly tightened up, as above described, the carriage sections may be forced apart or toward each other at various points along the length of the carriage, as may be required in making the final adjustment, by inserting the pivot portion 51 of the adjusting implement shank into the proper pivot hole 47 in plate 1 of the carriage, and then rotating the implement by handle 50 to cause the toe of the cam 52 to exert pressure against either the forward edge or the rear edge of the registering hole 48 in the carriage plate 6, as may be required to make the desired adjustment. The two sections of the carriage may be locked securely against relative movement after the final adjustment is made by tightly screwing up the clamping screws 10.

It is desirable that the teeth of the carriage feed rack 5 shall mesh with the teeth of the carriage feed pinion 53 to the proper depth. In the drawings a part of the rotary escape-mechanism similar to that embodied in

the Corona Four machine is shown, only so much of the escapement being shown as is necessary for a full understanding of the present improvement. In this escapement mechanism the feed pinion 53 and the escapement ratchet wheel 54 are held to a shaft journaled in a bushing 55, this bushing being swaged in a hole 56 formed in a bracket 57. In the present construction the flat body portion of bracket 57 is detachably and adjustably held to the bottom plate 35 of the carriage bed by a pair of fastening screws 58 passed upwardly through slots 59 in the bracket plate and threaded into screw holes in the base plate of the carriage bed, as shown in Figs. 2, 4 and 9. In order that the depth of mesh between the feed pinion teeth and the feed rack teeth may be adjusted, the flat body portion of the bracket is formed with the slots 59 through which the shanks of the screws extend, such slots extending transversely of the carriage bed or fore-and-aft of the machine, as shown in Fig. 4. The base plate 35 of the carriage bed is formed with a hole 60 registering with the hole 56 in the bracket 57 and affording clearance for the bushing 55.

In order that the extent of relative adjustment between the feed pinion 53 and the feed rack 5 may be readily observed, and the depth of mesh effected by adjustment of bracket 57 may be observed while the parts are assembled, the registering holes 47 and 48 of the two sections of the carriage are disposed over the feed rack 5, as clearly shown in Fig. 1, so that the intermeshing teeth of the feed pinion and rack may be observed through each set of registering holes 47 and 48 at different points in the travel of the carriage.

The spring - driven carriage - advancing drum 61 is rotatably held to the bottom of the carriage bed 35, adjacent one end of the bed, by supporting means 62, said supporting means being similar to that embodied in the Corona Four machine. In the present construction the usual carriage pull cord 63, attached to the drum 61 at one end, passes up through a slot 64 in the base plate 35 of the carriage bed and is attached to an anchor screw 65 (Figs. 1 and 5) threaded upwardly through the base plate 1 of the front section of the carriage adjacent the right-hand end of the carriage, said slot 64 and screw 65 being arranged on a line between the flange 45 on the front section of the carriage and the raceway flange 36 on the carriage bed. The cord 63 passes over a pulley 66 rotating in the slot 64. Pulley 66 is journaled on an axle formed of a short length of steel wire 68 forced through two sheet metal eyes 67 punched up from the base plate 35 of the carriage bed. Said eyes tightly embrace the wire pulley axle which is driven therethrough and rests on the top face of the plate 35, and one end of the wire at the outer side of one of

the eyes is bent laterally, thereby preventing accidental displacement of the pulley axle.

The carriage bed is provided with two sets of screw holes 69 for attachment of the bed to the upper ends of the obliquely shiftable 70 pair of raceway-carrying brackets of the shift frame of the Corona Four machine.

What I claim is:

1. A platen carriage for typewriting machines comprising two sections each formed of a single piece of sheet metal, one of said sections forming the front portion of the carriage and comprising a flat plate-like body portion having an integral carriage feed rack pendent from its rear edge and an integral raceway flange pendent from its forward edge and also having a pair of integral upstanding plate-like end portions at opposite ends thereof each formed with a platen shaft bearing, the other section forming the rear portion of the carriage and comprising a flat plate-like body portion overlapping the body portion of the first section and having an integral raceway flange pendent from its rear edge to the rear of the carriage feed rack, and means for securing said flat body portions of the carriage sections to each other in different relatively adjusted positions fore-and-aft of the carriage. 75 80 85 90

2. A platen carriage for typewriting machines comprising two sections each formed of a single piece of sheet metal, one of said sections forming the front portion of the carriage and comprising a flat plate-like body portion having an integral carriage feed rack pendent from its rear edge and an integral raceway flange pendent from its forward edge and also having a pair of integral upstanding plate-like end portions at opposite ends thereof each formed with a platen shaft bearing, the other section forming the rear portion of the carriage and comprising a flat plate-like body portion overlapping the body portion of the first section and having an integral raceway flange pendent from its rear edge to the rear of the carriage feed rack, the body portion of the front section having screw holes therein and the body portion of the rear section having slots therein extending fore-and-aft of the carriage and registering with the screw holes in the front section, and clamping screws having shanks passing down through the slots in the rear section and threaded into the screw holes in the front section. 95 100 105 110 115 120

3. A platen carriage as claimed in claim 2, in which the screw holes and slots are arranged in two rows extending longitudinally of the carriage and spaced apart fore-and-aft of the carriage, there being a plurality of said registering holes and slots in each row. 125

4. In a typewriting machine, a platen carriage having a base and platen-supporting end members, a support on which the carriage 130

is mounted for traveling movement, a feed rack held to the carriage under the carriage base and in a plane substantially parallel with the base, a feed pinion meshing with said rack and disposed in a plane substantially parallel with the carriage base, and means supporting the feed pinion under the carriage base for adjustment to vary the depth of mesh of the pinion and rack teeth, said carriage base having a series of apertures therein spaced apart longitudinally of the feed rack and disposed to permit observation of the relatively adjustable meshed rack and pinion at different points in the travel of the carriage from a view point above the carriage.

5. A two-part sheet metal platen carriage having opposed raceways, each of said carriage parts formed with one of said raceways along one longitudinal edge thereof, one of 10 said parts being formed with a pair of platen supports at its ends and with an integral flange along its other longitudinal edge having rack teeth for providing a carriage feed rack, and connecting means for holding the 15 two carriage parts rigidly together in different fore-and-aft adjusted relationship.

6. In a typewriting machine, a sheet metal carriage bed comprising a base plate having integral upstanding raceway flanges formed 20 with outwardly facing channels, a sheet metal carriage traveling over said bed and having a two-part base plate, one part of said base plate having a raceway flange pendent from its front edge in front of the forward raceway 25 flange of the bed and formed with an inwardly facing channel, the other part of said base plate having a raceway flange pendent from its rear edge behind the rear raceway flange on the bed and formed with an inwardly facing channel, said first-mentioned part of the 30 base plate being provided with an integral carriage feed rack located between the raceway flanges of the bed, means for locking the two parts of the base plate together in different fore-and-aft adjusted relation, and 35 antifriction roller elements confined in the raceways formed by the oppositely facing channels in each pair of juxtaposed raceway flanges.

7. A typewriting machine as claimed in 40 claim 6, wherein one of the base parts of the carriage is formed, with a pair of integral upstanding end plates for supporting a platen.

8. A typewriting machine as claimed in 45 claim 6, in which one of said carriage base parts is formed with integral stop lugs adjacent opposite ends thereof and a bracket is attached to the carriage bed substantially 50 mid-length of the bed and is formed with a pair of abutments each disposed in the path of movement of a different one of said stop lugs for determining the maximum limits of 55 travel of the carriage over the bed.

9. In a typewriting machine, a traveling

platen carriage having a sheet metal raceway element bent into concavo-convex form in cross section, a companion stationary sheet metal raceway element bent into concavo-convex form in cross section and arranged with its concave face facing the concave face of the carriage raceway element, said raceway elements each having a longitudinal row of integral rack teeth lying wholly within its longitudinal edges, said teeth consisting of 70 bent webs of metal extending across the line of bend of the raceway element separating the holes of a row of holes formed in each raceway element prior to the bending of the element into concavo-convex form and of greater 75 area at that face of the element which is to have the concave surface, a gear element having peripheral teeth meshing with the rack teeth of both raceway elements, an antifriction rolling element in the raceway formed 80 by said companion raceway elements, and a connection between said gear element and rolling element whereby said rolling element is constrained to travel the same distance as the gear element when the carriage is reciprocated.

10. In a typewriting machine, a platen carriage, a carriage bed, said carriage and bed having cooperating pairs of sheet metal raceway elements each bent into approximately 95 V-shape in cross section and arranged with the concave faces of the bed raceway elements facing the concave faces of the adjacent carriage raceway elements, each raceway element having a longitudinal row of rack-teeth-forming webs therein, each web extending across the line of bend of the raceway element of which it forms a part and having side edges flaring inward toward each other toward the concave face of the raceway element, 100 said webs of each row constituting the portions of the body of the raceway element intermediate the holes of a row of counter-sunk holes formed in the element prior to bending thereof along the line of bend and with the outwardly flaring end portions of said pre-formed countersunk holes adjacent that face of the element designed to form the concave face of the finished raceway element, a plurality of antifriction rolling elements between 110 each pair of cooperating raceway elements, a carrier in each raceway for said rolling elements maintaining the rolling elements in predetermined spaced relation longitudinally of the path of travel of the carriage, and a pinion 115 journaled on each carrier and meshing with the rack-teeth-forming webs of the two adjacent companion raceway elements.

11. In a typewriting machine, a carriage support, a carriage on the support having a base, a feed rack held to the carriage under the base, a feed pinion under the carriage base meshing with the rack, and means supporting the pinion for adjustment toward and from the rack, said carriage base having aper- 120 125 130

tures therein affording a view of the intermeshed rack and pinion from above the carriage.

12. In a typewriting machine, a pair of stationary raceway members, a platen carriage having a base comprising two overlapping plates each carrying a raceway member at its outer edge cooperating with one of the stationary raceway members, one of said plates having a plurality of screw holes therein spaced apart longitudinally of the carriage and the other plate having a plurality of slots registering with said screw holes and extending transversely of the carriage, clamping screws extending through said slots and threaded into said holes, said plates having registering apertures therein, the apertures in one plate being circular to afford a pivot bearing for the stub axle of a hand-operated rotary adjusting cam and the apertures in the other plate being larger than said circular apertures for engagement of said adjusting cam with walls thereof in expanding and contracting the carriage, and rolling elements interposed between the stationary raceway members and the raceway members carried by the carriage base.

13. In a typewriting machine, a sheet metal carriage bed having a base plate, a platen carriage mounted on the bed to travel thereover, a spring-driven carriage advancing drum having a draw cord attached thereto and to the carriage, said bed having a slot therein, means supporting the drum from the bed below the bed, a pulley turning in the slot in the bed, said bed having a pair of eyes punched up therefrom fore-and-aft of the slot, and an axle for the pulley extending fore-and-aft of the machine and driven tightly through said pair of punched up eyes, said draw cord passing from the drum through the slot in the carriage bed and over said pulley to its point of connection with the carriage.

14. A sheet metal carriage comprising flat overlapping front and rear base plate sections, a feed rack formed integrally with one section of the carriage, and means for adjustably clamping the sections together, each of said base plate sections having an integral raceway-forming portion at one longitudinal edge thereof, said raceway-forming portions being shiftable toward and from each other by relative fore-and-aft movement between the overlapped carriage base plate sections, said feed rack consisting of a flange extending along one longitudinal edge of one of the base plate sections between the raceway forming portions of the sections and provided with rack teeth.

15. A two-part sheet metal platen carriage comprising a main section having a flat base plate portion formed at its ends with integral platen-supporting end plates perpendicular thereto and formed along its opposite longi-

tudinal edges with an integral raceway flange and an integral flange provided along its longitudinal edge with rack teeth to form a feed rack, said raceway and rack flanges being disposed at the opposite side of said base plate portion of the main section from said end plates, and an auxiliary carriage section having a base plate portion overlapping and adjustably clamped to that side of the base plate of the main section at which the end plates are located, said auxiliary section being formed along one longitudinal edge with an integral raceway flange between which and the raceway flange on the main section the rack flange on the main section is located.

16. A two-part sheet metal platen carriage comprising a main section having a flat base plate portion formed at its ends with integral platen-supporting end plates perpendicular thereto and formed along its opposite longitudinal edges with an integral raceway flange and an integral flange provided along its longitudinal edge with rack teeth to form a feed rack, said raceway and rack flanges being disposed at the opposite side of said base plate portion of the main section from said end plates, an auxiliary carriage section having a base plate portion overlapping and adjustably clamped to that side of the base plate of the main section at which the end plates are located, said auxiliary section being formed along one longitudinal edge with an integral raceway flange between which and the raceway flange on the main section the rack flange on the main section is located, and each of said end plates on the main section being formed with an integral drawn tubular bearing for a platen shaft.

17. An adjustable platen carriage comprising two plate-like base sections, and means for rigidly connecting the sections in different adjusted relation crosswise of the carriage, each of said sections having its flat body part formed with an integral channel flange along one longitudinal edge thereof forming a raceway portion, the flat body part of one of said sections having an integral flange along its remaining longitudinal edge lying between the two raceway portions of the carriage and having its outer edge portion formed with rack teeth and bent into parallelism with the body part of said section to provide a carriage feed rack.

18. An adjustable platen carriage comprising two plate-like base sections, means for rigidly connecting the sections in different adjusted relation crosswise of the carriage, each of said sections having its flat body part formed with an integral channel flange along one longitudinal edge thereof forming a raceway portion, the flat body part of one of said sections having an integral flange along its remaining longitudinal edge lying between the two raceway portions of the carriage and having its outer edge portion formed with

- rack teeth and bent into parallelism with the body part of said section to provide a carriage feed rack, and one of said base sections having a pair of integral carriage end plates bent up from its ends and each provided with a bearing for a platen shaft.
19. In a typewriting machine, the combination of a sheet metal carriage bed comprising a base plate formed with upstanding longitudinal raceway flanges and also with an aperture substantially midway its ends, a sheet metal platen carriage comprising two overlapped base plate portions each formed with an integral pendent longitudinal raceway flange opposed to one of the faceway flanges of the bed, rolling elements in the races formed by said carriage and bed flanges, an integral L-shaped flange pendent from the remaining longitudinal edge of the lowermost base plate portion of the carriage and formed along its edge with rack teeth lying parallel with said base plate portion to form a carriage feed rack, platen supporting end plates carried by one of said base plate portions of the carriage, clamping and guiding means for connecting the overlapped base plate portions of the carriage for relative transverse sliding adjustment and locking the same in desired adjusted relation, a feed pinion shaft extending through the aperture in the carriage bed, a carriage feed pinion on said shaft meshing with the rack teeth on said toothed flange, and means held to the carriage bed for rotatably supporting said shaft and adjusting the shaft and pinion transversely of the L-shaped toothed carriage flange, said overlapped base plate portions of the carriage having a series of registering apertures therein spaced apart longitudinally of the feed rack and disposed to permit observation of the depth of mesh of the teeth of the relatively adjustable rack and pinion from above the carriage at different points in the carriage travel, the apertures in the lowermost base plate portion of the carriage being circular to afford a pivot bearing for the stub-axle of rotary carriage-adjusting cam wrench and the apertures in the uppermost base plate portion of the carriage being larger than said circular apertures for receiving the cam portion of the adjusting wrench.
20. An adjustable platen carriage having opposed raceway flanges comprising two overlapped base plate portions each carrying one raceway flange of the carriage, a carriage feed rack carried by one of said portions lying between said flanges with its teeth extending substantially parallel with the base plate portions, said base plate portions having a row of registering apertures spaced longitudinally of the feed rack and overlying the rack teeth, the apertures in the lowermost one of the overlapped base portions being smaller than those of the uppermost base plate portion, and means connecting said base plate portions for relative sliding adjustment crosswise of the carriage and locking thereof in adjusted relation.
21. A platen carriage having a sheet metal raceway part provided with integral rack teeth for a driving pinion for rolling elements traveling along said part, said raceway part being bent up longitudinally thereof from flat form, along a line bisecting the holes of a row of preformed countersunk holes therein, and having two angularly disposed longitudinal bearing surface portions for antifriction rolling elements located at opposite sides of the fold line and at that face where the countersunk holes had the greater original diameter, and also having a row of integral rack teeth for a rolling-element-driving pinion each of which teeth extends transversely of the raceway part across the line of bend thereof and has side edges flaring toward each other toward the rolling element engaging face of the raceway part.
22. A platen carriage support including a sheet metal raceway part cooperative with a carriage raceway part to form a race for anti-friction rolling elements, said raceway part of the support being bent up longitudinally thereof from flat form along a line bisecting the holes of a row of pre-formed countersunk holes in said part and having two angularly disposed longitudinal bearing surface portions for the anti-friction elements located at that face of the part at which the pre-formed holes had the greater original diameter and also having a row of integral rack teeth for cooperation with a rolling element-driving pinion, which teeth are narrowest at the rolling-element-engaging face of the raceway part and are formed by the webs of metal separating said countersunk holes in the raceway part.
- In testimony whereof I hereunto affix my signature.
